DESIGN FOR A RING OR SIMILAR ARTICLE.

Application filed January 25, 1926. Serial No. 16,257. Term of patent 14 years.

To all whom it may concern:

Be it known that I, BERTHOLD VEIT, a citizen of the United States, and a resident of the city of New York, borough of Manhattan, in the county and State of New York, have invented a new, original, and ornamental Design for Ring or Similar Article, of which the following is a specification, reference being had to the accompanying drawing, forming part thereof, wherein the ring is distinguished by means of an ornamental arrangement of a knotted rope as-

sociated with hands gripping the same and with hearts mounted thereon.

Figure 1 is a perspective view of a ring, showing my new design.

Figure 2 is an enlarged development of the ring shown in Figure 1 illustrating more exactly the design.

I claim:

The ornamental design for a ring or similar article, substantially as shown and described.

BERTHOLD VEIT.
